UNITED STATES PATENT OFFICE.

ROBERT EDWIN REARDON, OF OTTAWA, ONTARIO, CANADA.

SINK-STRAINER.

1,190,322.

Specification of Letters Patent. Patented July 11, 1916.

Application filed March 18, 1915. Serial No. 15,239.

To all whom it may concern:

Be it known that I, ROBERT EDWIN REARDON, a subject of the King of Great Britain, and resident of the city of Ottawa, Province 5 of Ontario, Dominion of Canada, have invented certain new and useful Improvements in Sink-Strainers, of which the following is a specification.

This invention relates to improvements in 10 sink strainers and the like particularly adapted for household use, and the objects of the invention are to facilitate in collecting and removing all solid matter suspended in the water which would be otherwise liable

15 to clog the waste pipe of the sink, to simplify the construction and cheapen the cost of manufacture, and generally to adapt the strainer to better perform the functions required of it.

20 The invention consists essentially of the improved construction particularly described and set forth in the following specification and accompanying drawing forming part of the same.

25 In the drawing, Figure 1 is a plan view of the disk prior to flanging. Fig. 2 is a plan view of the completed strainer. Fig. 3 is an enlarged sectional elevation of the same.

30 Like characters of reference refer to like parts in the several drawings.

Referring to the drawing, A represents the improved strainer which primarily consists of a paper or like disk 10 having a plurality of serrations 11 around its periphery and being further provided with a plurality of orifices 13 through the center thereof. This disk is then flanged as shown at 14 and provided with a concentric depression or 40 well 15 in the top.

To give rigidity to the completed strainer I preferably flute the supporting flange 14, the said flutings extending radially inwardly on the depressed top toward the per 45 forated center and terminating just short of the same. This strainer is designed to be located in the corner of a sink or the like with the serrated flange 11 resting thereon and the water to be run into the sink is

emptied into the well 15 where the solid matter is collected, while the liquid passes through the orifices 13 and finally drains off through the serration 14 in the flange to the waste pipe. The function performed by the flutings in the top of the strainer is to 55 more readily run the liquid into the well 15 so that there is little or no liability of the solid matter lodging on the edge of the strainer and becoming inadvertently precipitated into the sink. Although this 60 strainer is adapted to be made of paper, it will be understood that other materials may be used with equal success.

As many changes could be made in the above construction and many apparently 65 widely different embodiments of my invention, within the scope of the claims, constructed without departing from the spirit or scope thereof, it is intended that all matter contained in the accompanying specification and drawings shall be interpreted as 70 illustrative and not in a limiting sense.

What I claim as my invention is:

1. A self-contained paper garbage container and sink strainer, comprising a concave perforated dish portion and an integral supporting flange depending from the periphery thereof at an acute angle thereto, said supporting flange having an intersticed lower edge to drain the sink water 80

2. A self-contained paper garbage container and sink strainer, comprising a radially fluted concave perforated dish portion and an integral fluted supporting flange depending from the periphery thereof at an acute angle thereto, the flutings on said parts registering at the point of juncture to strengthen the structure at the point of the angle, said supporting flange having a plurality of interstices at its lower edge to 85 drain the sink water.

In witness whereof I have hereunto set my hand in the presence of two witnesses.

ROBERT EDWIN REARDON.
